CONTROL CABINET FOR MEDICAL ELECTRONICS

Elmer A. Piat, Cleveland, Ohio

Application January 18, 1935, Serial No. 39,327

Term of patent 14 years

(Cl. D38-14)

FIG. 1

Fig. 2

Fig. 3

Figure 1 is a front elevation of the control cabinet for medical electrodes, embodying my new design;

Figure 2 is a right end elevation of the same; and

Figure 3 is a rear elevation of the same.

I claim:

The ornamental design for a control cabinet for medical electrodes, substantially as shown.
